UNITED STATES PATENT OFFICE.

LEOPOLD BRANDEIS, OF BROOKLYN, NEW YORK.

FAUCET.

SPECIFICATION forming part of Letters Patent No. 288,769, dated November 20, 1883.

Application filed June 18, 1883. (No model.)

To all whom it may concern:

Be it known that I, LEOPOLD BRANDEIS, a citizen of the United States, and a resident of Brooklyn, in the county of Kings and State of New York, have invented certain new and useful Improvements in Faucets, of which the following is a specification.

My invention relates to that class of faucets in which the valve is connected to a crank within the casing; and it consists in the construction fully described hereinafter, whereby faucets of this character are rendered available as basin-faucets and for other purposes.

In the drawings, Figure 1 represents in longitudinal section a basin-faucet illustrating my improvement. Fig. 2 is a modification.

The casing A of the faucet is of any suitable construction, and adapted for connection to either vertical or horizontal supply-pipes, as the occasion may require, and is provided with an annular seat, x, to which is fitted a valve, D, the stem B of which receives the crank end of a spindle, G, extending into the casing. The spindle G extends through a suitable packing-box, so that it may be turned to rotate the crank and carry the valve to and from its seat without the passage of water around the spindle to the outside of the casing.

Heretofore valve-faucets having the construction above described have had solid spindles provided with handles, and casings with nozzles at the outer ends.

To adapt the faucet for use with wash-basins and for other purposes, I close the outer end of

the casing, as shown in the drawings, and use 35 a tubular spindle, either open at the lower end, Fig. 1, or with perforations i, Fig. 2, through which water can pass through the interior to the outer end, which is provided with or formed into a suitable nozzle.

In some cases the handle by which the spindle is turned may be hollow and constitute the nozzle of a faucet, as in the drawings, where the nozzle I is connected by a hollow sphere, b, with the spindle. As thus constructed the 45 swinging of the nozzle I to one side or the other turns the spindle and carries the valve to and from its seat.

Without limiting myself to the precise construction and arrangement of parts shown, I 50 claim—

1. The combination, in a faucet, of a casing, A, provided with the seat x, a hollow spindle, G, having a crank end within the casing, and a valve, D, provided with a stem, B, receiving the crank end of the spindle, substantially 55 as set forth.

2. The combination, with the casing A, valve D, hollow crank-spindle G, connected with the valve, and nozzle I, communicating 60 with the spindle, substantially as set forth.

In testimony whereof I have signed my name to this specification in the presence of two subscribing witnesses.

LEOPOLD BRANDEIS.
